(57) **CLAIM**

The ornamental design for a part of a parasol, as shown and described.

DESCRIPTION

FIG. 1 is a top, front and left side perspective view of a part of a parasol, showing my new design;

FIG. 2 is a top, right, and front view thereof;

FIG. 3 is a front view thereof, with the rear view being a mirror image thereof;

FIG. 4 is a right side view thereof;

FIG. 5 is a left side view thereof;

FIG. 6 is a top view thereof; and,

FIG. 7 is a bottom view thereof.

The ends of the post shown in broken lines throughout the figures indicate the boundary of the claimed design, and the broken line circle in FIG. 5 shows elements of the part of the parasol that forms no part of the claimed design.
